UNITED STATES PATENT OFFICE.

KARL MATHEUS, OF CHICAGO, ILLINOIS.

BELT AND THE LIKE.

1,422,999.

Specification of Letters Patent.

Patented July 18, 1922.

Application filed August 29, 1921. Serial No. 496,295.

To all whom it may concern:

Be it known that I, KARL MATHEUS, a citizen of the United States, residing at Chicago, in the county of Cook and State of Illinois, have invented certain new and useful Improvements in Belts and the like, of which the following is a specification.

This invention has to do with improvements in belts. It has reference particularly to certain improvements in extension devices which may be used in conjunction with belts and the like so as to permit them to stretch and contract under spring pressure.

One of the objects of the invention is to provide an improved contractile device which is very well adapted to this class of service. In this connection one of the objects is to provide a contractile device of such form that it may be very easily and cheaply manufactured and from a very small number of parts so that it will not readily get out of order. Another object of this invention is to provide a contractile device of such construction as to make provision for a relatively large amount of expansion and contraction so as to increase the capacity of the device in this connection.

Another feature of the invention relates to the manner in which the contractile device is related to the end portions of the belt itself. In this connection the object is to make provision for very readily hooking together the end portions of the belt itself, while at the same time effectively protecting the inside faces of the contractile device so that the articles of clothing and the like will not readily become wedged or jammed in the contractile device itself.

Other objects and uses of the invention will appear from a detailed description of the same, which consists in the features of construction and combinations of parts hereinafter described and claimed.

In the drawing:

Figure 1 shows a perspective view of the end portions of a belt, having applied thereto a contractile device embodying the features of the present invention;

Fig. 2 shows a face view of the mechanism of the contractile device itself with the two

sections thereof drawn together under spring pressure;

Fig. 3 shows a view similar to that of Fig. 2, with the exception that the two sections have been drawn apart to the limit of permissible movement;

Fig. 4 shows a longitudinal section taken on the line 4—4 of Figs. 1 and 2 looking in the direction of the arrows; the housings being removed; and

Fig. 5 shows a back face view of that end portion of the belt which carries the contractile device.

I will first describe the construction of the contractile device itself. It includes a pair of companion plates 6 and 7 in conjunction with an intermediate slide plate 8 and springs 9 and 10. The plates 6 and 7 are provided with guide blocks 11 and 12 which receive the ends of the slide plate 8 and serve to maintain the end plates 6 and 7, as well as the slide 8, in alignment with each other. The guide blocks 11 and 12 may be of any suitable construction but are conveniently made in the form of separate sheet metal plates riveted to the plates 6 and 7.

The slide plate 8 carries the pins 13 and 14 at its ends, which pins are adapted to engage recesses 15 and 16 in the guide plates 11 and 12 at the extreme limit of movement of the parts. The springs 9 and 10 may be of any convenient construction, but the form illustrated in Figs. 2 and 3 is very satisfactory. The springs illustrated are of spiral wire and have their inner ends 17 and 18 anchored on pins secured to the end plates 6 and 7. The free ends of these spiral springs are hooked onto the links 19 and 20, the other ends of said links being pivoted to the central portion of the slide plate 8 by the pins 21 and 22 respectively.

It will be observed from the drawing that the pivotal pins 21 and 22 are offset from each other instead of being located in a direct longitudinal line. There is consequently set up a turning effort on the slide plate 8, but the guide blocks 11 and 12 effectively resist this turning effort and keep all of the parts properly lined up.

It will also be observed that the tension on both of the springs is the same and that

the springs are placed in tandem with each other, so that the total amount of permissible extension is equal to the sum of the individual extensions. In this way a very 5 even and satisfactory operation is secured while at the same time the contractile or expandible capacity of the device is double in amount.

The contractile device is intended to be set 10 into a portion of the belt structure where it will be subjected to the tension of the belt and where it may extend and contract, allowing the end portions of the belt the proper amount of relative movement. For 15 this I have illustrated the following arrangement: One end 23 of the belt is directly connected to the end plate 6. A supplemental belt section 24 is connected to the end plate 7. The extension and contraction 20 takes place between the belt sections 23 and 24. The other end of the belt proper is shown at 25, and is provided with a series of perforations 26 located at convenient distances apart, and the supplemental belt section 25 carries a hook 27 which may be set into a selected one of the perforations 26 so as to adjust the size of the belt to the needs of the wearer.

The end section 25 is carried past the inside faces of the supplemental section 24 and of the contractile device, so as to overlap the contractile device in the manner indicated particularly in Figs. 1 and 4. This overlapping serves to protect the garments 30 of the wearer from possible entanglement with the contractile device. In order to hold the belt end portion 25 in proper position, I have shown a wire loop 28 as connected to one of the sections of the contractile device, the belt end 25 being passed therethrough.

I have also shown the end plates 6 and 7 as being stamped out into such form as to offset their extreme end portions 29 and 30 45 an amount substantially equal to the thickness of the belt material. This will bring the contractile device into direct alignment with the belt material, as clearly shown in Fig. 4. The end portions 29 and 30 may 50 also be provided with the prongs 31 which are connected to the belt sections by being passed through the material thereof. A facing 32 of thin leather or other suitable material may be placed over the back surfaces 55 of the portions of the contractile device so as to finish the same and provide a neater construction. In like manner suitable caps or housings 33 and 34 may be secured over the front portions of the contractile members 60 so as to inclose the same and give the device a neat and finished appearance. One of the members 33 or 34 may be provided with a tongue 35 adapted to reach over into the other in telescoping fashion so as to protect the contractile mechanism at all times,

and a design 36 on the front face of the box members 33 and 34 may in such case be continued over the tongue 35, as shown in Fig. 1, to give a continuous finished appearance to the device.

70

I claim:

1. As a new article of manufacture, a contractile device for belts and the like, comprising in combination a pair of end plates each having its end portion offset substantially the thickness of belt material, belt sections set into said offset portions, means for securing each offset portion to the corresponding belt section, guide blocks on the end plates having longitudinally extending 75 guide passages, a slide plate having its end portions working within said guide blocks, pins on said slide plate, limiting its movement in the extension direction, a coil spring on each end plate having one end connected 80 to such end plate, links joining the free ends of said springs with the central portion of the slide plate, and suitable housings secured to both end plates and covering over and protecting the springs, links and slide 85 plate, substantially as described.

2. As a new article of manufacture, a contractile device for belts and the like, comprising in combination a pair of end plates, belt sections secured thereto, guide blocks 95 on the end plates having longitudinally extending guide passages, a slide plate having its end portions working within said guide blocks, pins on said slide plate limiting its movement in the extension direction, a coil 100 spring on each end plate having one end connected to such end plate, links joining the free ends of said springs with the central portion of the slide plate, and suitable housings secured to both end plates and covering over and protecting the springs, links and slide plate, substantially as described.

3. As a new article of manufacture, a contractile device for belts and the like, comprising in combination a pair of end plates, belt sections secured thereto, guide blocks on the end plates having longitudinally extending guide passages, a slide plate having 110 its end portions working within said guide blocks, pins on said slide plate limiting its movement in the extension direction, a coil spring on each end plate having one 115 end connected to such end plate, and links joining the free ends of said springs with the central portion of the slide plate, substantially as described.

4. As a new article of manufacture, a contractile device for belts and the like, comprising in combination a pair of end plates, 125 belt sections secured thereto, guide blocks on the end plates having longitudinally extending guide passages, a slide plate having its end portions working within said guide blocks, a coil spring on each end plate hav- 130

ing one end connected to such end plate, and links joining the free ends of said springs with the central portion of the slide plate, substantially as described.

5 5. As a new article of manufacture, a contractile device for belts and the like, comprising in combination a pair of end plates, belt sections secured thereto, guide blocks

on the end plates having longitudinally extending guide passages, a slide plate having 10 its end portions working within said guide blocks, and a spring between each end plate and the central portion of the slide plate, substantially as described.

KARL MATHEUS.
